UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

1,425,223.

Specification of Letters Patent. Patented Aug. 8, 1922.

Application filed March 1, 1920. Serial No. 362,310.

To all whom it may concern:

Be it known that I, HAROLD G. WARR, a citizen of the United States, residing at Park Ridge, in the county of Cook and 5 State of Illinois, have invented certain new and useful Improvements in Rail Anchors, of which the following is a specification.

My invention relates to devices for resisting longitudinal movement of railroad 10 rails, such devices being known generally as rail anchors, rail stays or anti-creepers, and has for its primary object to provide an improved device of this character which when applied to a rail will serve to resist 15 any tendency of the rail to move longitudinally in either direction.

A more specific object of the invention is to provide a device or rail anchor part which may be used in connection with any 20 one of various types of rail anchors that are now employed to resist longitudinal movement of rails in one direction only, for giving such an anchor capacity for maintaining a firm grip on the rail during a retrograde movement whereby the combined 25 anchoring device will resist any movement of the rail in either forward or rearward directions.

The invention has for further objects, the 30 novel arrangements, constructions and combination of parts and devices hereinafter described and claimed for carrying out the above stated objects and such other objects as will appear from the following specification.

The invention is illustrated in certain preferred embodiments in the accompanying drawings, wherein:

Fig. 1 is a plan view of a rail anchoring 40 device constructed in accordance with my invention and showing the device in its operating position on a railroad rail.

Fig. 2 is a section taken on line 2--2 of Fig. 1, showing the rail in section and the 45 rail anchoring device in elevation.

Fig. 3 is a view in perspective of the additional rail anchor part of the combined anchoring device illustrated in Figs. 1 and 2.

Fig. 4 is a plan view similar to Fig. 1 50 illustrating a modification.

Fig. 5 is a plan view illustrating another modification, a portion of the rail being broken away for the purpose of clearness.

Fig. 6 is a view taken on line 6--6 of 55

Fig. 5 showing the rail in section and the rail anchoring device in elevation.

Fig. 7 is a view in perspective of the additional rail anchor part in the combined anchoring device illustrated in Figs. 5 60 and 6.

Fig. 8 is a fragmentary view partly in section taken on line 8--8 of Fig. 5 looking in the direction indicated by the arrows, and 65

Fig. 9 is a plan view illustrating a further modification.

Like characters of reference designate like parts in the several figures of the drawings. 70

In the embodiment of the invention shown in Figs. 1 to 3 inclusive, the rail anchoring device consists of a shoe member 10, a yoke member 11 having an interlocking engagement with the shoe and a fastening member 75 13 for anchoring the yoke member to a cross tie 14. The shoe member 10 is provided with a recess 15 which fits over one edge of the base flange of the rail 16 and is formed with a tie abutting foot 17 adapted to bear 80 against one of the vertical faces of the tie 14 when the shoe is applied in its operative position on the rail. The yoke member is a spring metal bar formed at one end with an angular hook 18 providing a jaw which 85 fits over the edge of the rail base opposite the shoe 10 and is provided at its other end with an upstanding portion 19 which extends around the shoe and fits in a recess 90 20 formed in the outer face thereof.

It is unnecessary, for a complete understanding of this invention, to further describe the specific construction of the shoe 95 10 and spring yoke 11 as these members are preferably constructed and applied in the same manner as the rail anchor device disclosed in the patent to D. F. and D. L. Vaughn No. 1,021,387, granted March 26th, 1912; the construction and application of which device, together with the manner in 100 which the spring yoke is subjected to a torsional strain to maintain its interlocking engagement with the shoe and to maintain its firm grip on the rail, being understood by persons familiar with this art. 105

The device disclosed in the above mentioned Vaughn patent is one form of the general type of rail anchor adapted to resist the longitudinal movement of a rail in one direction only. My invention, in this form, 110

is, therefore, in the nature of an improvement upon the Vaughn anchor and in its broader aspect aims to provide means which may be readily used in connection with various forms of rail anchors of the general one way type, whereby the said anchors may be employed to resist movement of a rail in a rearward direction as well as forwardly. This result is accomplished in the embodiment shown in Figs. 1 to 3 inclusive, by the use of fastening member 13 which, preferably, consists of a bar having an opening 21 at one end through which the jaw portion 18 of the spring yoke 11 extends and having a shank portion 22, angular in cross section, providing a lip which bears against the upper surface of one of the base flanges of the rail. The fastener 13 is preferably held in firm engagement with the rail base and cross tie by spikes 24-24. The yoke engaging portion of the fastener 13 is preferably formed with an outwardly curved portion 25 which engages the jaw portion 18 of the yoke 11 so as to insure a firm engagement between the yoke and fastening member when the yoke assumes various angular positions across the base of the rail. The opening 21 of the fastener is preferably large enough to permit a slight relative movement between the yoke 11 and the fastener so as to permit the yoke to increase its grip on the rail during a creeping pressure of the rail toward the tie.

When the anchoring device is in its operative position the spring yoke 11 preferably extends diagonally across the rail base as indicated in Fig. 1. Any longitudinal movement of the rail in a direction toward the tie 14 carries the jaw 18 of the yoke with it and thereby increases the grip of the device on the rail; the said jaw, under such conditions, taking a biting hold on the vertical edge of the rail base. If the rail moves longitudinally in the rearward direction from the tie with which the shoe 10 engages, the jaw 18 of the yoke is held in a relatively fixed position by means of its engagement with the fastening member 13, and the shoe 10 and end 19 of the spring yoke move rearwardly with the rail thus increasing the grip of the device on the rail and resisting the movement thereof.

The modified anchoring device shown in Fig. 4 of the drawings is the same as that described in connection with Figs. 1 to 3 inclusive, except that the recess designated 20^a in the outer face of shoe 10^a, instead of being relatively shallow as shown in Fig. 1, extends through the outer wall 10^b of the shoe so as to permit the upstanding portion 19^a of the spring yoke 11^a to take a biting hold on the vertical edge of the rail in addition to having an interlocking engagement with the shoe member. The other parts of this form of invention are designated by the

same reference characters as shown in Fig. 1.

Referring to the modification illustrated in Figs. 5 to 8 inclusive: This embodiment of the invention employs, as one of its members, the device disclosed in the patent to Lewis O. Henggi, No. 1,167,299 granted January 4th, 1916, which device consists of a relatively heavy spring yoke member adapted to grip the upper and lower surfaces of a rail base with spring pressure and abut against one of the vertical faces of a cross tie so as to resist movement of the rail in one direction only. The spring yoke is designated in the drawings as 26 and consists of a steel bar, the ends of which are bent over to form hooks providing jaws 27, 28 having substantially the same degree of inclination as the upper surface of the base flanges of the rail. The portion of the yoke intermediate the ends, preferably nearer the jaw 27 than the jaw 28, is bent upwardly to provide a seat 29 which bears against the under surface of the rail base. The yoke is applied to the rail by inserting the jaw 28 over one of the base flanges of the rail and raising the jaw 27 to the position shown in dotted lines in Fig. 6. The jaw 27 is then driven upon the base flange until the yoke assumes the full line position shown in Fig. 6. The yoke, abutting against one of the vertical faces of the tie, resists any tendency that the rail may have to move longitudinally toward the tie 30.

In the above embodiment, any tendency of the rail to move in a direction away from the tie 30 is resisted by a hook-shaped fastening member 31 which extends around one of the jaws of the yoke, preferably jaw 27, and is spiked to the tie 30, as indicated at 32. The hook member 31 is bent over at one end to provide a jaw 33 which fits over one edge of the rail base and engages with the rear face of the jaw 27 of the yoke member. The jaw portion 33 of the hook 31 is given a normal set at a slight angle with relation to the body of the hook so that when the body portion is forced upon the inclined surface of the rail base the jaw 33 of the hook will exert a pinching grip on the rail base which prevents looseness and vibration.

In the modification shown in Fig. 9, a fastening member 31^a of the same construction as that shown in Figs. 5 to 8 inclusive, is employed in connection with a one-piece spring metal anchor of the type disclosed in my application for Letters Patent Serial No. 295,555 filed April 29, 1919, which device consists of a piece of spring metal 36 formed to extend diagonally across the rail base, one end of which is formed with a jaw 37 which takes a biting hold on the rail during the presence of a creeping pressure and the other end being formed in a loop 38 providing a tie abut-

ment 39. The loop end 38 of the anchor is formed with a vertically extending shoulder or jaw 40 and an overhanging jaw 41, the latter of which is sprung into engagement with the rail by forcing the loop end of the anchor from the dotted position to the full line position and thereby subjecting the anchor to a torsional strain which produces an initial spring grip of the device on the rail. It will be noted that by using the attachment 31 as shown in Fig. 9, the anchor device will resist either forward or rearward movements of the rail. With either movement of the rail the grip of jaws 37, 40 on the rail is increased. When the rail moves forwardly the jaw 37 tends to move with the rail, the rail movement being checked because this would involve increasing the obliquity of member 36. When the rail moves backwardly, or tends to move backwardly, its actual movement to any appreciable extent is checked because the loop end 38 of member 36 would move with the rail if the rail moved, while jaw 37 would be restrained from movement away from the tie by its bearing on member 31^a. Thus the co-operative relation between the members of the anchoring device is the same as that which exists in the forms of the invention shown in Figs. 1 to 4 inclusive.

While the invention is thus illustrated in certain preferred embodiments, it will be obvious that further modifications might be made without departure from the spirit of the invention. It will, therefore, be understood that the invention contemplates all such modifications that come within the scope of the appended claims.

I claim:

1. In a rail anchoring device, the combination or rail base gripping means adapted to engage with a cross tie to resist longitudinal movement of the rail in one direction, and a separate fastening device for anchoring said rail base gripping means to the tie, whereby longitudinal movement of the rail in the opposite direction is resisted.

2. In a rail anchoring device, the combination with means engaging a rail and abutting one of the cross ties whereby movement of the rail toward the tie is resisted, of means for resisting movement of the rail in a direction away from the tie comprising a separate fastening device engaged with said rail base engaging member and anchored to the tie.

3. In a rail anchoring device, the combination of a rail engaging member provided with means adapted to abut against a cross tie to resist movement of the rail in one direction and a fastening member anchored to the tie and engaging said rail engaging member to resist movement of the rail in the opposite direction; said engagement between said members being adapted to

permit slight relative movement of said members whereby an increased grip of the device is effected during the presence of a creeping pressure on the rail.

4. A rail anchoring device comprising a rail base gripping member provided with means to bear against a tie and adapted to resist longitudinal movement of the rail in one direction, and a separate fastening device engaging one of the base flanges of the rail and adapted to anchor said rail gripping member to said tie so as to resist movement of the rail in the opposite direction.

5. A rail anchoring device comprising rail base gripping means adapted to abut against a cross tie to resist movement of the rail in one direction, and means for anchoring the aforesaid means to the tie to resist movement of the rail in the opposite direction comprising a fastening member engaging the tie and adapted to fit over a portion of said rail base gripping means.

6. A rail anchoring device comprising rail base gripping means adapted to grip a rail with spring pressure and abut against a cross tie to resist movement of the rail in one direction, and means for anchoring the aforesaid means to the tie to resist movement of the rail in the opposite direction comprising a fastening member engaging the tie and adapted to fit over a portion of said rail base gripping means.

7. A rail anchoring device comprising a rail base gripping member adapted to grip a rail with spring pressure and provided with means to abut against a cross tie and adapted to resist movement of the rail in one direction, and means for attaching said member to the tie to resist movement of the rail in the opposite direction comprising an angular bar secured to the tie so as to clamp the rail base to the tie and formed at one end with an opening which fits over a portion of said rail base gripping member.

8. A rail anchoring device comprising a rail base engaging member provided with means to bear against a cross tie and adapted to resist movement of a rail in one direction, and means for resisting movement of the rail in the opposite direction comprising a fastening device engaged with the tie and having a jaw adapted to engage with the rail gripping member and take a pinching grip on the rail base.

9. A rail anchoring device comprising a rail base gripping member adapted to engage with a cross tie to resist movement of the rail in one direction, and means for resisting movement of the rail in the opposite direction comprising a fastening device engaged with the tie and having a jaw adapted to engage with the rail gripping member which device is subjected to a bending strain when applied to its operative position on the rail.

10. A rail anchoring device comprising a rail base gripping member adapted to engage with a cross tie to resist movement of the rail in one direction, and means for resisting movement of the rail in the opposite direction comprising a fastening device engaged with the tie and formed with a jaw which fits over one edge of the rail base and engages the rail base gripping member, said 10 jaw being formed with a normal set at an angle to the body portion of the fastening device whereby said device is strained in its application to the rail.

11. In combination with means adapted 15 to engage a rail and to bear against a tie to prevent the rail from moving longitudinally in one direction, of means engaging the aforesaid means and said tie for resisting longitudinal movement of the rail in the 20 opposite direction.

12. In combination with means adapted to engage a rail and to bear against a tie to prevent the rail from moving longitudinally in one direction, of means engaging the aforesaid means and anchored to said tie for resisting longitudinal movement of the rail in the 25 opposite direction.

13. A rail anchoring device comprising rail gripping means adapted to bear against 30 a tie and to have its hold on the rail increased by a tendency of the rail to move forwardly, and means whereby said hold is also increased when the rail tends to move in the opposite direction.

14. A rail anchoring device comprising a 35 rail base embracing member adapted to extend diagonally across said rail base, and tie engaging means separable from said rail base embracing member adapted to engage with opposite ends thereof. 40

15. A rail anchoring device comprising a rail engaging member adapted to extend across the bottom of the rail diagonally thereof and tie engaging members engaged by opposite ends respectively of the rail 45 engaging member, one of which bears against a tie and the other of which is anchored to said tie.

16. A rail anchoring device comprising a rail engaging member adapted to extend 50 under the rail diagonally thereof and provided at one end with means for abutting against a tie, and a member anchored to said tie which engages the other end of the rail engaging member but so as to permit said end to move forwardly with a forward movement of the rail. 55

17. A rail anchoring device comprising a spring steel rail engaging member adapted to extend under the rail diagonally thereof and provided at one end with means for abutting against a tie, and a member anchored to said tie which engages the other end of the rail engaging member but so as to permit said end to move forwardly with a forward movement of the rail. 60 65

HAROLD G. WARR.
